UNITED STATES PATENT OFFICE.

HUGO BERQUIST, OF SWISSVALE, PENNSYLVANIA, ASSIGNOR TO WILLIAM S. ELLIOTT, OF PITTSBURGH, PENNSYLVANIA.

LIQUID-TREATING APPARATUS.

Application filed March 29, 1922, Serial No. 547,868. Renewed December 29, 1926.

The present invention relates broadly to liquid treating apparatus, and more particularly to apparatus of this character adapted to degasify or deaerate water for use in heating systems, boiler installations, economizers, and the like to decrease the incrustation producing or corrosive properties of the water.

It has heretofore been customary in apparatus of this general character, as illustrated for example in the patent to W. S. Elliott No. 1,321,999 of November 18, 1918, to provide a series of separate organized pieces of apparatus to carry out the various functions. Such separate pieces are assembled in any desired relationship, one exterior to the other, by the use of suitable piping or connections. Such a construction not only involves a great deal of expense, but also entails a certain loss of pressure due to the resistance to vapor flow through the connecting piping or passages. This is particularly true of the flow between the evaporating chamber and the condenser. The result is necessarily a loss or decrease of efficiency. By the present invention these objectionable features are obviated, and advantageous results are produced.

I have also found that where vapor enters a condenser through a relatively restricted inlet there is apt to result a flow through the nests of tubes localized at the point where the vapor is introduced. This operation results from the use of separate units or pieces of apparatus assembled as referred to. By an organization in accordance with the present invention I am able to produce a uniform flow through the condenser, and also to maintain therein the desired vapor velocity.

In the accompanying drawings there is shown for purposes of illustration only one embodiment of the present invention. It will be understood that changes may be made in the construction and operation of the apparatus disclosed and described herein without departing from the spirit of the invention or scope of my broader claims. As the invention becomes better understood by reference to these drawings and the accompanying specification, the foregoing and other desirable objects and advantages will become apparent.

In the drawings:

Fig. 1 is a side view, partly broken away,

illustrating one embodiment of the invention;

Fig. 2 is a sectional view on the line II-II of Fig. 1, and,

Fig. 3 is an end elevation of the left hand end of the apparatus illustrated in Fig. 1.

This invention is concerned primarily with that class of apparatus in which the liquid to be treated is first heated and then enters a chamber wherein there is maintained a pressure such that a portion of the liquid evaporates. This evaporation is due to an instantaneous boiling or exploding of the liquid resulting from the liberation of heat supplied by the liquid itself. This results in the release of the entrained air and gases, the condensable portion of which is condensed. This condensing is preferably effected in such manner that the heat released by the vapors and gases is utilized.

In carrying out the present invention there may be provided a container 2 preferably of generally cylindrical shape having removable heads 3 and 4. This container, in accordance with the present invention, may constitute a casing within which are arranged all or part of the different units utilized in effecting the desired treating operation of the liquid. With this form of my invention the liquid to be treated may be supplied to the apparatus through a suitable inlet connection 5 communicating with a chamber 6 on the head 4. This chamber is in turn adapted to deliver the liquid to a portion of the tubes 7 of a two pass condenser located within the container 2. The opposite ends of the tubes 7 discharge the liquid into a header 8 carried by the head 3. This header delivers the liquid to the other tubes 7 of the two pass condenser, which tubes are effective for returning the liquid to the header 6 provided with an outlet connection 11 which may lead to any desired form of feed water heater located at any desired point with respect to the container 2. In some instances I have found it desirable to position the feed water heater entirely within the container 2.

After leaving the feed water heater in which it is raised to any desired temperature, the liquid is adapted to be delivered to a master controlling valve 12, the flow through which may be controlled by a suitably arranged float operated mechanism 13 actuated by the level of the liquid within

the container 2 in any desired manner. After leaving the master controlling valve 12, the liquid is adapted to be delivered through a suitable connection 14 to one or 5 more secondary valves 15. These valves 15 are preferably of the construction shown and claimed in my co-pending application, Serial No. 536,371, filed February 13, 1922. In accordance with this form of my invention 10 the secondary valve comprises a chamber 16 preferably vertically disposed and of such depth as to permit the accumulation of any desired head of water above the valve 15. Extending upwardly from each 15 of the valves, and secured thereto in any desired manner, is a valve stem 17 which passes through a suitable bushing or packing 18 in the casing 19. The upper end of each of the valve stems is preferably screw 20 threaded to receive an adjustable follower head 20 by means of which the compression of the spring 21 may be varied as desired. The upper end of the valve stem, and also 25 the compression spring, may be enclosed in any desired manner as by a removable cap 22.

Where a secondary valve of this construction is utilized, it will be apparent that the compression spring may be adjusted to any 30 desired extent to thereby determine the static head of water within the chamber 16 necessary to open each of the valves. For example, if the spring is so set that the static head necessary to overcome the tension 35 thereof is equivalent to two feet of water, as soon as the water rises in the chamber to a distance of two feet above the outlet of the valve it will immediately begin to open. As the head of water increases, 40 the extent to which the valve opens likewise increases. This insures a uniform velocity of discharge by means of which the rate of distribution and manner of distribution can be accurately controlled.

45 For effecting a further breaking up and distribution of the liquid, the secondary spray valve is adapted to deliver the liquid to suitably arranged distributor 23 in the chamber 24 within the container 2. The 50 spring of the secondary spray valve naturally restrains the opening of the valve, whereby the liquid will issue into the chamber 24 with considerable velocity. This, in combination with the distributor, effectively 55 breaks up the liquid into fine particles or thin sheets, enabling the entrained gases and vapors to immediately free themselves from the liquid.

Within the chamber 24 I maintain a pressure 60 having such a value that the heated liquid sprayed thereinto will be instantly boiled or exploded, due to the release of a portion of its contained heat, resulting in the partial evaporation of the liquid and 65 the instantaneous release of the entrained

air and gases. For example, if I maintain within the chamber 24 a pressure of five pounds per square inch absolute, water would boil in this chamber at a temperature of approximately 162° F. If the temperature of the water immediately before it passes the valve 15 is in excess of 162° F., a portion of it will be evaporated.

The vapor released during this evaporation, together with the released gases, will 75 enter the condenser and pass around the tubes 7. Due to the location of the condenser within the container 2, there may be an opening 25 therein extending the entire length, or a major portion of the length, of 80 one side of the condenser. This permits a uniform flow through the nests of tubes within the condenser of a character which can not be produced when the vapor and gases are locally supplied to the condenser 85 through a restricted inlet. Furthermore, with a condenser of the construction illustrated, it will be apparent that the area available for the flow of the vapor and gases therethrough decreases toward the outlet 90 95 100 105 pressure, but it will be understood that the utility of the invention is not limited in this respect. With this form of my invention, the secondary condenser, provided where an ejector is utilized, may obviously be eliminated. Such an ejector and secondary condenser is disclosed and claimed in my divisional application Serial No. 198,912 filed June 15, 1927. In the form shown,

10 the non-condensable gases escape directly to the atmosphere through the outlet 26. With this construction, the raw liquid before it goes to the heater will pass through the tubes of the primary condenser, and 15 after leaving the heater will pass through the master control valve and the secondary valve into the chamber 24. The temperature of the liquid in the heater will preferably be raised to a temperature in excess of that 20 corresponding to atmospheric pressure.

In some cases it may be desirable or necessary to reduce the temperature of the liquid after it has been treated in the chamber 24 and the air and gases removed therefrom.

25 In such cases I may provide a heat exchanger 30 placed in the bottom of the chamber 24, through which the raw liquid to be treated may pass on its way to the primary condenser. Within the heat exchanger there may be provided a series of 30 chambers 31 having communicating openings 32 between adjacent chambers, the openings being located adjacent different ends of the exchanger whereby a tortuous 35 path of travel therethrough is provided. The treated liquid flows from the chamber 24 into the exchanger through the inlet 33 and is adapted to leave the exchanger through the opening 34. The outlet opening 40 communicates with a chamber 35 with which the outlet connection 36 for withdrawing the treated liquid communicates.

Located within the chambers 31 of the heat exchanger are tubes 37 communicating 45 with headers 38 and 39 on the respective heads 3 and 4 of the apparatus. These headers are suitably constructed to produce the desired flow through the tubes 37 whereby the raw liquid entering the inlet 40 is 50 caused to travel through the heat exchanger and absorb therein the heat given up by the treated liquid. From the heat exchanger this partially heated liquid may pass to the inlet 5 of the primary condenser. With this 55 construction a considerable heating surface is provided whereby the treated liquid leaves the apparatus at a temperature considerably lower than 212° F., or the temperature maintained within the chamber 24.

60 By the present invention there is provided an apparatus which utilizes advantageously the spaces within the chamber of the container, thereby reducing the cost of inde-

pendent condensers and heat exchangers necessary for the practice of this system of 65 liquid treatment. The apparatus is compact, accessible and may be inexpensively installed. It thus possesses many advantages over apparatus as heretofore provided for this general purpose.

70

I claim:

1. In a liquid treating apparatus, a container having an evaporating chamber therein, means for spraying liquid into said chamber to permit the release of air and gases 75 from the liquid, means within said chamber for reducing the temperature of the liquid after the escape of the air and gases therefrom, and means within said chamber for condensing the condensable portion of the 80 air and gases released from the liquid, said two last mentioned means being connected in series.

2. In a liquid treating apparatus, a container having a liquid space and a vapor space, a heat exchange unit located in said liquid space, a heat exchange unit located in said vapor space, both of said units comprising a series of tubes, and means for passing 85 the liquid to be treated in series into and through the tubes of said units.

3. In a liquid treating apparatus, a container having a liquid space and a vapor space, a plurality of heat exchange units in 90 said vapor space, a heat exchange unit in said liquid space, all of said units comprising a series of tubes, and means for passing the liquid to be treated successively into and through the tubes of said units.

4. In a liquid-treating apparatus, a container having a liquid space and a vapor space, a heat exchange unit located in said liquid space, a heat exchange unit located in said vapor space, and means for passing 95 the liquid to be treated first through said first mentioned unit and then through said second mentioned unit in series.

5. In a liquid-treating apparatus, a container having a liquid space and a vapor space, a heat exchange unit in said liquid 100 space, a plurality of heat exchange units in said vapor space, and means for passing the liquid to be treated successively into and through all of said units with the liquid passing first through the heat exchange unit in said liquid space.

6. In a liquid treating apparatus, a container having a liquid space and a vapor space, a heat exchange unit located in each 105 of said spaces, each of said units comprising a series of tubes, and means for passing the liquid to be treated through the tubes of said units in series.

In testimony whereof I have hereunto set my hand.

HUGO BERQUIST.
